CASEDaniel M. Ganz, Forest Hills, and Roy G. Feiner,
Long Beach, N. Y.

Application November 1, 1952, Serial No. 22,102

Term of patent 14 years

(Cl. D86—3)

To all whom it may concern:

Be it known that we, Daniel M. Ganz and Roy G. Feiner, citizens of the United States of America, residing at 63—15 110th Street, Forest Hills, Long Island, New York; and 106 Harding Avenue, city of Long Beach, Nassau County, New York, respectively, have invented a new, original, and ornamental Design for a Combination Cigarette and Vanity Case, of which the following is a specification, reference being had to the accompanying drawing, forming part thereof.

In the drawings:

Fig. 1 is a top perspective view of a combination cigarette and vanity case, showing our new design; and

Fig. 2 is a front perspective view showing the combination cigarette and vanity case in opened position.

The side opposite the side shown in Fig. 1 is substantially plain.

We claim:

The ornamental design for a combination cigarette and vanity case, substantially as shown and described.

DANIEL M. GANZ.
ROY G. FEINER.
